SWITCH UNIT

**Anthony Venditty, Detroit, Mich., assignor to
Thompson Products, Inc., Cleveland, Ohio, a
corporation of Ohio**

**Original application August 23, 1943, Serial No.
499,604. Divided and this application October
27, 1945, Serial No. 625,052**

5 Claims. (Cl. 200—6)

1

This invention relates to a switch unit and more particularly to a simple, compact reliable switch structure which is particularly suitable for use in controlling electric motors on equipment used or installed in the home.

This application is a division of my copending application entitled "Switch unit," U. S. Serial No. 499,604, filed August 23, 1943, and assigned to the same assignee as the present invention.

One of the principal features and objects of the present invention is to provide a novel compact switch unit for controlling the flow of high voltage current such, for example, as the current usually supplied by public utility companies at 110 to 120 volts, 60 cycle A. C.

A further object of the present invention is to provide a novel switch structure housed in a single compact assembly.

Another object of the present invention is to provide a novel switch and mounting therefor which is economical to manufacture and which is rugged and reliable in use.

The novel features which I believe to be characteristic of my invention are set forth with particularity in the appended claims. My invention itself, however, both as to its organization and manner of construction, together with further objects and advantages thereof, may best be understood by reference to the following description taken in connection with the accompanying drawings, in which:

Figure 1 is a diagrammatic view of a switch unit embodying the novel teachings and characteristics of the present invention and showing it with a motor which it is designed to control and a pushbutton switch which effects operation of the main switch unit, the switch unit being complete and assembled except that the sealing compound is removed from the grooves in the cover;

Figure 2 is a plan view of the switch unit shown in Figure 1;

Figure 3 is a bottom view showing the under side of the cover which has been removed from the switch unit;

Figure 4 is a sectional view of the unit as shown in Figure 2 as taken along the line IV—IV thereof with the cover now in place;

Figure 5 is a sectional view of the unit with the cover in place as taken along the line V—V of Figure 2;

2

Figure 6 is a section view of the unit with the cover in place as taken along the line VI—VI of Figure 2;

Figure 7 is a sectional view of the upper portion of the unit with the cover in place as taken along the line VII—VII of Figure 2;

Figure 8 is an isometric view of the solenoid bracket;

Figure 9 is a plan view of the upper housing member of the unit; and

Figure 10 is a diagrammatic illustration of an electric circuit in which the novel switch of the present invention may be employed, and indicates the utility of the switch structure.

15 In order to understand the problem involved, and in order to fully appreciate one of the useful circuits in which the novel switch structure of the present invention may be used, reference will first be made to Figure 10 of the drawings, 20 wherein is diagrammatically illustrated a split-phase induction motor 11 which is arranged to be energized from supply conductors 12 and 13. Supply conductors 12 and 13 are arranged to be connected to a suitable source of alternating current supply, such, for example, as the conventional 110 volt 60 cycle current which is usually supplied by the public utility companies throughout the country. The motor 11 has four terminal connections which have been labeled R, G, O and B. Although not shown, it will be understood by those skilled in the art that the terminal connections R and B are connected to one winding of the split phase induction motor 11 while the terminal connections G and O are connected to 35 the other winding, the latter having a resistance element in series therewith.

The motor 11 is connected to supply conductors 12 and 13 through a switch 14. This switch 14 has six stationary contacts 15 to 20, inclusive, and 40 three movable contact bars 21, 22 and 23 which are carried on a bar of insulating material 24 and arranged to be rocked about the longitudinal axis of this bar. The contact bar 21 is arranged to be rocked into engagement with either stationary contact 15 or stationary contact 18. Contact bar 22 is arranged to be rocked into engagement with either stationary contact 16 or stationary contact 19. Contact bar 23 is arranged to be rocked into engagement with either stationary 45 contact 17 or stationary contact 20. Contact bars 50

21 and 22 are connected together by bus 25 and to supply conductor 13 through conductor 26. Contact bar 23 is connected to supply conductor 12 through conductor 21.

Stationary contacts 15 and 18 are electrically connected together and to terminal B of motor 11 through conductor 28. Stationary contacts 16 and 20 are electrically connected together and are also connected to terminal O of motor 11 through conductor 29. Stationary contacts 17 and 19 are electrically connected together and are also connected to terminal G of motor 11 through conductor 30. The terminal R of motor 11 is directly connected to supply conductor 12 through conductor 31.

It will be understood by those skilled in the art that when the insulating bar 24 is rocked in a counterclockwise direction as shown in Figure 10 of the drawings, movable contact bars 21, 22 and 23 will be moved into engagement with stationary contacts 18, 19 and 20 and the motor will operate in one direction. When the insulating bar 24 is rocked about its longitudinal axis in a clockwise direction, movable contact bars 21, 22 and 23 will be moved into engagement with stationary contacts 15, 16 and 17, and the motor will be operated in the other direction.

The control and operating circuit for rocking the bar 24 includes a pair of solenoids 31 and 32 and a step down transformer 33. Transformer 33 includes a primary winding 34 and a secondary winding 35. The winding 34 is connected across the supply conductors 12 and 13 as shown. The ratio of the number of turns in the secondary winding 35 to the number of turns in the primary winding 34 is such that current at low voltage is supplied through conductors 36 and 37. It is preferable that the current supplied through conductors 36 and 37 have a voltage of between 6 to 10 volts.

Conductor 36 is connected to one end of the solenoid 31 and also to one end of the solenoid 32. The opposite end of solenoid 31 is connected to a switch contact 38 through conductor 39 while the opposite end of solenoid 32 is connected to a switch contact 40 through conductor 41. Two additional contact elements 42 and 43 are provided which are associated with contacts 38 and 40 respectively and which are connected through conductor 37 to the lower end of secondary winding 35 of transformer 33. Contacts 38 and 42 are arranged to be closed by a movable switch element 44 while contacts 40 and 43 are arranged to be closed by a movable contact element 45. Contact elements 44 and 45 are normally biased to their open position.

Transversely mounted on the insulating bar 24 is an armature arm 46 which is made of iron or some other suitable magnetic material. When the contact 44 is closed, solenoid 31 is energized from transformer 33 and the left-hand portion of the armature 46 is pulled down, thus rocking the bar 24 in a counter-clockwise direction about its longitudinal axis. On the other hand, if contact element 45 is closed, solenoid 32 is energized and the right-hand portion of armature 46 is pulled down, thus rocking the bar 24 in a clockwise direction about its longitudinal axis.

The compact unitary nature of the invention is exemplified by the particular physical embodiment illustrated in Figures 1 to 9 of the drawings. In the form shown, a single closed housing 10 comprising lower and upper housing members 47 and 48 are provided for the transformer 33, the solenoids 31 and 32 and the switch 14.

This housing, which is preferably formed of some suitable molded material of good insulating qualities, is so shaped as to provide a transformer compartment 49, a solenoid compartment 50 and a switch compartment 51. To this end, the lower housing member 47 has an upper wall portion 52 which extends entirely over the compartment 49. Downwardly extending shoulders 53 and 54 are formed at either end of the wall portion 52 to provide a suitable seat for the laminated iron core 55 of the transformer 33. The compartment 49 is further closed off by a panel 56 which extends across the lower open end of the housing member 47. As is clearly shown in Figures 4 and 6, the end wall 57 is tapered as at 58 and the wall portion 59 is tapered as at 60. This permits ready insertion of the transformer 33 through the lower opening in the housing member 47 when the panel 56 is removed.

The base wall 61 of the solenoid compartment 50 is slightly offset from the remaining base walls of the housing member 47 formed by the panel 56. The solenoids 31 and 32 are mounted on a T-shaped iron bracket 62 and secured by means of bolts 63 to the base wall portion 61. The solenoids 31 and 32 are of conventional design and include iron cores 64 and 65 respectively. The bolts 63 are threaded into the lower end of these iron cores 64 and 65 to thus secure the solenoids in place. The bracket 62 has a cut-away portion 66 which forms a shoulder on which the armature arm 46 is arranged to be seated (see Figure 8).

A C-shaped bracket is molded as an integral part of the upper wall member 52 and includes a base portion 67 and two upstanding lips 68 and 69. This bracket supports and confines the tongue 92 at one end of the bar 24 which carries the movable contact elements 21, 22 and 23. The armature arm 46 is secured to the bar of insulating material 24 by a bolt 93, and the central portion of arm 46 which extends beyond the end of bar 24 is slotted as at 94 (see Figure 2). This slotted portion 94 is arranged to receive the upstanding top portion 95 of the bracket 62, while the unslotted central portion of the arm 46 is arranged to be seated on the shoulder 66 of the bracket 62. The bar 24 is thus arranged for rocking movement about its own longitudinal axis.

The bar 24 has three transverse grooves 71, 72 and 73 in the upper surface thereof which are arranged to have metal contact arms 21, 22 and 23 seated therein. In the center of each groove 71, 72 and 73 a pin projects upwardly therefrom. More particularly, pins 74, 75 and 76 extend through the bar 24 as may be seen best in Figure 4. Each of the contact arms 21, 22 and 23 is provided with a circular opening through the center which is slightly larger than the pin, as is indicated at 77, 78 and 79 (see Figure 2). Since it is necessary to electrically connect contact arms 21 and 22, a flat electrical connector 25 is seated on the same, suitable apertures 96 being provided in the strip 25 to permit the pins 74 and 75 to extend therethrough. For a reason which will presently be apparent the strip 25 is also provided with an upstanding protuberance 97 at its center.

The ends of the contact arms 21, 22 and 23 are provided with contact buttons 80 which are arranged to engage the confronting buttons 81 on the stationary contacts 15 to 20, inclusive. Due to the fact that the openings 77, 78 and 79 in the contact arms 21 to 23 are somewhat larger than the pins 74 to 76 it will be apparent that the contact arms 21 to 23 may have limited rock-

ing movement on the bar 24 about one or the other end of each of their associated grooves, depending upon which direction the bar 24 is rocked.

The bar 24 is resiliently held in place by a pair of coil springs 82 and 83 which are seated in the recess portions 84 and 85 respectively of the upper housing member 48. The lower end of the coil spring 82 is seated directly on the contact strip 25 over the protuberance 97, while the lower end of the coil spring 83 extends over the pin 76 and is seated on the contact arm 23. It will thus be clear that not only is the bar 24 resiliently held in place, but the contact arms 21, 22 and 23 are also resiliently held in their respective recessed seats on the bar 24.

The upper surface of the upper housing member 48 is provided with four transverse grooves 86, 87, 88 and 89 which are preferably of the shape and configuration as illustrated in Figures 4, 6, 7 and 9 of the drawings. As either end of each transverse groove 86 to 89, a copper or brass bushing 90 extends through the wall of the upper housing member 48. As is clearly shown in Figure 6 of the drawings, the bushings 90 in each of the grooves 86, 87 and 88 are arranged to receive the stationary contact buttons 81. The upper end of each bushing 90 is threaded and set screws 91 are threaded therein. Each of the two bushings 90 in the end groove 89 is provided with a set screw 98 at the outer end and also a set screw 99 at the inner end.

The terminal set screws 98 are arranged to be connected to the A. C. supply conductors 12 and 13 (as shown diagrammatically in Figures 1 and 10). The set screws 99 (which are electrically connected to screws 98 through the bushings 90) clamp the ends of the conductors 100 and 101 leading from the primary 34 of the transformer. They also receive and clamp pigtail conductors 26 and 27 which extend from contact arms 22 and 23 respectively.

A partition wall 102 between grooves 87 and 88 in the upper housing member 48 is broken out as at 103 to permit conductors 104 and 105 to extend therethrough. As shown in Figure 10, conductor 104 connects contact buttons 17 and 19, while conductor 105 connects buttons 16 and 20. Contact buttons 15 and 18 are connected together by a conductor 106 which extends across the bottom of the groove 86.

Since the electrical connections between the motor 11 and the unit 10 are designed to be permanent, the grooves 86 and 89 are preferably filled with an insulating compound of the type which hardens when cooled and forms a substantially permanent part of the housing member 48.

The upper and lower housing members 48 and 47 are secured together by bolts 107. A pair of feet 108 may be molded or otherwise formed in the lower housing member 47 to enable the unit to be secured in any desired position.

Low voltage push button switches 44 and 45 are preferably contained in a small separate housing 109, while the conductors 39, 41 and 37 which connect the push button switches 44 and 45 to the control circuit of the main switch contained in the unit 10 are preferably confined in a single cable 110. The conductors 39, 41 and 37 are connected respectively to guiding posts 111, 112 and 113 on the exterior end wall 114 of the lower housing member 47. The electrical connections between the push button switches 44 and 45 and the main unit 10 are arranged to be made by any inexperienced person, and since only low voltage

flows in this external circuit no professional electrician is required. The conductors 28, 29, 30 and 31 which extend between the motor 11 and the unit 10 are preferably contained in a well insulated cable 115, the connections at both ends being made substantially permanent at the factory at the time that the motor 11 and the unit 10 are assembled. Although relatively high voltage flows through the conductors in the cable 115, it is not necessary to have a professional electrician since no change is to be made in these connections at the time that the motor 11 is installed. The alternating current power source is connected to the unit 10, as previously described, to conductors 12 and 13. These conductors 12 and 13 are preferably contained in a cable 116 having a male plug member 117 at their ends which is arranged to be plugged into a conventional 110 volt 60 cycle alternating current socket (not shown).

When the motor 11 and the unit 10 are installed in a position where the motor is to be used (such, for example, as in a private garage for operating the main garage doors), the power supply cable 116 is plugged in by the male plug member 117 into a suitable outlet box. The box 109 containing the push button switches 44 and 45 is then mounted any place desired and a cable is run from the box 109 to the terminals 111, 112 and 113 of the unit 110. When the push button switch 44 is depressed, the solenoid 31 is energized and the bar of insulating material 24 is rocked in a counter-clockwise direction as viewed in Figure 10. This causes the movable contact arms 21, 22 and 23 to engage the stationary contact buttons 18, 19 and 20 respectively. Similarly, when the push button 45 is depressed rather than push button 44, solenoid 32 is energized and the bar 24 is rocked in a clockwise direction about its own longitudinal axis to cause the contact arms 21, 22 and 23 to make an electrical contact with their associated stationary contact buttons 15, 16 and 17 respectively. Figure 5 shows the position of the movable contact arm 21 as it is moved into position against its associated stationary contact 15. It will be observed that not only is the bar 24 rocked in a clockwise direction about its longitudinal axis, but the arm 21 itself has a rocking movement with respect to the bar 24. This rocking movement of contact arm 21 with respect to the bar 24 is a relative counter-clockwise movement of the arm 21. This causes a wiping action between the contact button 80 on the end of the arm 21 over the contact button 81 which forms the stationary contact 15. Furthermore, due to the fact that the coil spring 82 tends to retain the contact arm 21 seated flat in its associated recess 71 in the bar 24, it will be apparent that the contact button 80 is held resiliently pressed against the contact button 81. A similar action occurs between the other confronting contact buttons upon movement of the bar 24 to one or the other of its extreme positions.

When both solenoids 31 and 32 are deenergized, the springs 82 and 83 cause the bar 24 to remain in its intermediate position as shown in Figure 6.

While I have shown a particular embodiment of my invention, it will, of course, be understood that I do not wish to be limited thereto, since many modifications may be made and I therefore contemplate, by the appended claims, to cover all such modifications as fall within the true spirit and scope of my invention.

I claim as my invention:

1. A switch unit comprising a supporting struc-

ture, an elongated member mounted on said supporting structure for rocking movement about its longitudinal axis, two groups of stationary contacts on said supporting structure on opposite sides of said elongated member, a plurality of contact arms seated in a transverse position on said elongated member, means for resiliently holding said contact arms in seated engagement against said elongated member, said contact arms being free to have relative rocking movement about either side edge of said elongated member and against the resilient action of said means about an axis above said elongated member, said contact arms and said two groups of stationary contacts being positioned so that one group of stationary contacts are engaged by said arms when said elongated member is rocked on its axis in one direction and the other group of stationary contacts are engaged by said arms when said member is rocked on its axis in the other direction, and means for rocking said elongated member.

2. A wiping contact pressure switch comprising supporting means, a stationary contact on said means, a member pivotally mounted for rocking movement on said means, a contact arm seated on said member, means for resiliently urging said arm in a straight line downwardly against said member, said arm having a contact portion arranged to engage said stationary contact when said member is rocked, said contact arm being initially moved about the pivot axis of said member until said contact portion engages said stationary contact, and said contact arm thereafter having relative angular movement about an edge of said member and movement in line with said resilient means against the resilient action of said resilient means, whereby a wiping pressure contact is made between said contact portion and said stationary contact.

3. A double throw switch comprising supporting means, an insulated member mounted on said supporting means and arranged for limited rocking movement, a pair of stationary contacts disposed on opposite sides of said rocking member, said member having a surface presenting a generally flat seat, a contact arm having contact portions at opposite ends arranged to engage said stationary contact, said contact arm being seated on said seat, means providing a movable pivot for said contact arm above said seat, means resiliently urging said arm against said seat, said pivot above said seat being movable in a line corresponding to the line in which said resilient means acts, and means for rocking said insulating member to selectively place one of said contact portions of said arm in engagement with one of said stationary contacts, said contact arm being initially moved about the axis of rock of said insulating member by movement of the latter until one of said contact portions engages one of said stationary contacts, and said contact arm thereafter having relative angular movement with respect to said insulating member about an edge of said seat surface and

about said movable pivot, whereby a sliding pressure contact is made between said contact arm and said stationary contacts.

4. A switch unit comprising supporting structure, a member mounted on said supporting structure for pivotal movement, at least one stationary contact on said supporting structure, at least one contact arm having an opening in the center thereof, a pin projecting from said member and loosely receiving the opening in said contact arm for relative rocking motion of the arm on said pin, means for resiliently holding said contact arm in seated engagement on said pin of said elongated member and for permitting said relative rocking motion of the arm against the resilient opposition thereof, said contact arm being initially moved about the pivot axis of said member until said arm engages said stationary contact, and said contact arm thereafter having relative rocking movement about an edge of said elongated member as well as with respect to said pin against the resilient opposition of said resilient means, whereby a wiping pressure contact is made between said contact arm and said stationary contact.

5. A compact switch unit comprising an insulating housing including upper and lower housing members, an elongated member mounted on said lower housing member for rocking movement about its longitudinal axis, two groups of stationary contacts on said upper housing member on opposite sides of said elongated member, a plurality of contact arms seated in a transverse position on said elongated member, means for resiliently holding said contact arms in seated engagement on said elongated member, said contact arms being free to have relative rocking movement about the side edges of said elongated member and against the resilient action of said means about said elongated member, said contact arms and said two groups of stationary contacts being positioned so that one group of stationary contacts are engaged by said arms when said elongated member is rocked in one direction and the other group of stationary contacts are engaged by said arms when said member is rocked in the other direction, and a low voltage switch operation mechanism for rocking said elongated member and disposed in said lower housing.

ANTHONY VENDITTY.
